US00D641393S

(12) **United States Design Patent**
Kim et al.

(10) **Patent No.:** **US D641,393 S**
(45) **Date of Patent:** **** Jul. 12, 2011**

(54) **PRINTER**

(75) Inventors: **Hoon-Tae Kim**, Seoul (KR); **Gisuke Ota**, Seoul (KR); **Bong-Uk Lim**, Kyunggi-do (KR); **Yun-Gi Hong**, Kyunggi-do (KR)

(73) Assignee: **Samsung Electronics Co., Ltd.**, Suwon, Kyunggi-Do (KR)

(**) Term: **14 Years**

(21) Appl. No.: **29/315,577**

(22) Filed: **Jul. 7, 2009**

(51) LOC (9) Cl. **18-02**

(52) U.S. Cl. **D18/14; D18/15**

(58) Field of Classification Search **D18/14, D18/15-21, 50, 51, 36; D14/308; 101/327, 101/333; 400/88; 347/109; 358/1.118**

See application file for complete search history.
